UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

1,409,426.

Specification of Letters Patent. Patented Mar. 14, 1922.

Application filed June 2, 1921. Serial No. 474,368.

To all whom it may concern:

Be it known that I, EDWARD S. STIMPSON, a citizen of the United States, residing at Hopedale, in the county of Worcester and 5 State of Massachusetts, have invented an Improvement in Warp Stop Motions for Looms, of which the following description, in connection with the accompanying drawings, is a specification, like characters on 10 the drawings representing like parts.

This invention relates to warp stop motions for looms, whereby upon the occurrence of a warp fault, such for instance, as breakage or undue slackness of a warp 15 thread, the loom is stopped.

It is desirable at times to run the loom without causing stoppage thereof, due to a warp fault. These occasions arise, for instance, when a new warp is placed in the 20 loom. At such time it is desirable to run the loom for a time to condition the warp and bring the warp threads into uniform tension and arrangement for the weaving operation. Such operation without stop- 25 ping due to a warp fault, may also arise where there has been a "smash" or other condition that has disturbed the general arrangement and tension of the warp threads.

The novel features and new combination 30 of parts will best be made clear from the following description in connection with the accompanying drawings, which show one good, practical form of carrying the various features of the invention into practical 35 effect.

In the drawings:

Figure 1 is a partial side elevation of 40 a loom provided with a warp stop motion embodying the present invention, some of the parts being broken away to show others beyond;

Fig. 2 is a detached perspective view showing more particularly portions of the warp 45 stop motion devices in separated relation, and the connection between such devices and the loom stopping mechanism;

Fig. 3 is a perspective view of one end 50 portion of the warp stop motion of the present invention, showing the feeler carrier removed from operative relation with the drop wires;

Fig. 4 is a fore-and-aft vertical section through the warp stop motion proper, the drop wires being indicated as supported in

their raised position by the normal warp 55 threads;

Fig. 5 is a similar section through the warp stop motion proper, showing more particularly the braces for bracing the drop 60 wire guides and the feelers.

As indicated in Fig. 1, the warp stop motion proper is located between the shedding mechanism or heddles and the rear of the loom, and in the present instance is associated with mechanism actuated by the 65 lay when a feeler is arrested in its detecting movement, to thereby knock-off the shipper and effect loom stoppage. The illustrated form of the mechanism between the warp stop motion proper and the shipper constitutes 70 a good, practical train of mechanism for effecting the desired purpose, but it is to be understood that the invention is not restricted thereto, but that the warp stop motion may be associated with any desirable train of mechanism which will serve 75 to bring the loom to rest when the detecting movement of a feeler is stopped by a drop wire.

The loom frame 1 may be of usual construction provided with a suitable support at the rear portion thereof for the warp beam 2 on which the warp threads are wound. Pivotedly mounted at 3 is the shipper 4 which, when the loom is running, may 80 be held in the usual shipper notch. Pivotedly mounted at 5 is the knock-off lever 6, one end 7 of which bears against the shipper and another portion whereof is connected at 8 to a link 9 extending, in the 85 present instance, rearwardly of the loom, the construction being such that a longitudinal movement of the link 9 rearwardly will serve to turn the knock-off lever 6 contraclockwise, Fig. 1, and thereby detach the 90 shipper from its holding notch, to effect loom stoppage.

The link 9 has its rear end connected at 10 to an arm 11 pivotally supported at 12 to the loom frame or a bracket 13 secured 100 to the side thereof. Mounted for rocking movement on the arm 11 is the dog 14, Fig. 2, having a pin 15 which extends into the slot 16 of a controller 17 which is secured on a rocker 18 mounted in a suitable bearing 105 formed in the bracket 13. The lay 19 has connected thereto the bunter 20, preferably adjustable, as by the slot and bolt connec-

tion 21 as indicated in Fig. 1, the construction being such that should the end of the dog 14 be in position for engagement with the bunter 20 as the lay moves back, 5 the rocker arm 11 will be moved counter-clockwise and thereby exert a pull upon the link 9 to effect loom stoppage by knocking-off the shipper. The mechanism so far described is or may be of usual construction, 10 such for instance, as generally shown and described in the patent to Ambler, Number 885,130, dated April 21, 1908, but so far as the novel features of the present invention are concerned, other forms of transmitting 15 mechanism may be employed between the warp stop motion proper and the loom stopping mechanism for effecting loom stoppage when a feeler is arrested in its detecting movement by a drop wire.

20 Mounted transversely to the loom frame is the rock shaft 22 which may receive a rocking movement from a cam 23 on the roller or cam shaft 24 through a train of mechanism which, in the present instance of the 25 invention, comprises a cam follower 25, Fig. 1, pivotally mounted at 26 at the lower part of the loom, and having an end portion 27 which bears against the cam 23 under the impulse of a spring 28, one end of which 30 is connected to the cam follower 25 at 29, and the other end portion of which is connected at a fixed point 30. Pivotally connected to the cam follower 25 at 31 is the rod 32, the upper end portion of which is 35 connected at 33 to an arm 34 secured to and extending from the rock shaft 22, the construction being such that upon rotation of the cam 23 the cam follower 25 will be rocked upon its bearing and will be held 40 against the cam by the spring 28 so long as the rock shaft 22 is free for rocking movement clockwise in the present instance.

Secured to the rock shaft 22 is the transmission arm 35, Figs. 1 and 2, which is connected by a link 36 with an arm 37 secured to the rocker 18, which, as hereinbefore described, controls the position of the dog 14. The construction is such that should the rock shaft 22 be arrested in its rocking movement clockwise, in the present instance, under the action of the spring 28, the dog 14 will be positioned to be met by the bunter 20 as the lay goes back, to thereby knock-off the shipper and stop the loom. The train 55 of mechanism which has been described forms a convenient construction for the purposes stated, but if desired, such train of mechanism may be varied without departing from the true scope of the present invention.

The loom frame 1 has adjustably secured thereto at each side of the loom, a bracket 38, the top supporting flange 39 of which is provided with a slot 40, Figs. 2 and 3. Ad- 65 justably supported upon the bracket 38 at

each side of the loom is a bracket 41 which may be formed with a slot 42 through which passes the securing bolt 43, the construction being such that the bracket 41 at each side of the loom may be readily removed from or 70 adjustably secured in place upon the bracket 38.

The two brackets 41, one at each side of the loom frame, provide supporting means for the main portions of the warp stop motion. In the present instance each bracket 41 has an upwardly-extending flange portion 44, between which extend the drop wire guides 45, three being shown in the present instance, though any suitable number may 75 be employed. Each of the drop wire guides 45 extends through the slotted portions 46 of a series of drop wires 47, Fig. 3. The drop wires 47 are formed with enlarged upper portions 48, and where more than one 80 series of drop wires is employed, such wires are arranged in parallel rows, as indicated in Fig. 3.

The drop wires 47 are adapted to be supported by the warp threads *a*, and for this 90 purpose may be provided with suitable warp-engaging portions which in the present instance of the invention consist of eyes 49 through each of which a warp thread is passed, as indicated in Figs. 1 and 3.

Extending between the flanges 44 of the brackets 41 are the warp supporting bars 50, four being shown in the present illustration, and upon the warp supporting bars 50 the warp threads *a* rest as they travel from the 100 warp beam toward the front of the loom. If desired, a warp separating or lease rod 51 may extend between and separate alternate warp threads, and be held from movement with the threads toward the front of the 105 loom by means of check cords or stops 52, Fig. 3.

The drop wire guides 45 are supported above the plane of the warp threads, as indicated in Figs. 1 and 3, and the end portions 110 of such guides are detachably secured to the flange portions 44 of the brackets 41. In the present instance of the invention, the flange portions 44 of the brackets 41 are recessed at intervals as at 53, thereby forming 115 lugs 54 against which the end portions of the drop wire guides are held by removable clips. In the present instance of the invention, the removable clips are formed of angular-shaped metal parts provided with a flange 55 which overlies the end portions 120 of the drop wire guides and each clip is provided with a securing portion 56 having a slot 57 through which passes a securing bolt 58, the construction being such that by loosening the bolts 58, the clips may be moved from overlying relation with the ends of the drop wire guides, so that they may be readily removed with the drop wires, when, for instance, a new warp is to be drawn in. 125 130

Associated with each row of drop wires is a feeler which is given a detecting movement and which, when arrested in such movement by one of the drop wires, effects loom stoppage.

As hereinbefore stated, it is desirable at times to run the loom without stopping, due to a fault in the warp, and for this purpose the present invention provides a feeler mechanism which may be moved from operative relation with the drop wires at will so that even though a warp thread should break or one or more of such threads be too slack for good weaving purposes, the loom will continue to run so long as the feeler mechanism is not in operative relation with the drop wires.

Each of the flange portions 44 of the brackets 41 is provided with guiding supports 59 which may be conveniently formed on opposite portions of the flanges 44, and upon such guiding supports rest the side members 60 of a feeler carrier which may be designated as a whole as 61, Figs. 2 and 3. Extending between and secured to the side members 60 of the feeler carrier are the feelers 62, any number of which may be employed, but three being shown in the present illustration of the invention. The side members 60 of the feeler carrier are provided with lug portions 63, against which are secured the feelers 62 by suitable means such as the securing bolts and nuts 64, the construction being such that they may be readily secured to or removed from the side members of the feeler carrier. The side members 60 of the feeler carrier are connected by a member or bar 65, the end portions of which preferably extend beyond the side members as at 66 to afford engaging portions with an actuator, whereby the feeler carrier may be given a reciprocating movement on its guiding supports 59. In the present instance the side members 60 have arms 67 extending therefrom, and provided with sleeves 68 which may be clamped to the bar 65 by set screws 69, Fig. 2, the construction being such that the side members of the feeler carrier are connected together not only by the feelers 62, but also by the members 65.

The rock shaft 22 hereinbefore described, may be conveniently supported in bearings 70 formed in the brackets 41, and extending from the rock shaft 22, preferably one at each end portion thereof, is an arm 71 having an open or bifurcated upper portion 72 in which may be received the end portion 66 of the member 65, the construction being such that upon rocking movement of the rock shaft 22, the feeler carrier will be given a reciprocating movement upon its guiding supports 59 and impart detecting movement to the feelers toward and from the associated row of drop wires.

As a preferable form of construction, the side member 60 of the feeler carrier has end bearing portions 73 which rest upon one of the guiding supports 59, while the end portion 66 of the feeler carrier may be supported by a shoulder or saddle 74, Fig. 2, adjustably mounted on the arms 71, the construction being such that the weight of the feeler carrier is preferably supported by the saddles 74 at one end, and the other end 75 by the bearing portions 73 of the side members 60. The saddles 74 are adjustably secured to the arms 71 to thereby enable proper relation of the feelers and the associated parts to be secured.

The feelers 62 are supported by the feeler carrier above the warp threads, thereby lessening the space occupied by the feeler mechanism proper in proximity to the warp beam and permitting a ready movement of the feelers from their operative relation with the drop wires to permit the loom to be run without stopping, due to a warp fault.

The feelers 62 are mounted above the warp threads in an inclined position relative to the plane of the warp threads, thereby enabling the feelers to be formed of sufficiently heavy metal to withstand the checking action of the drop wires without bending, and such inclined position of the feelers also prevents the accumulation of lint upon the feelers, which might otherwise interfere with the delicate operation of the mechanism.

In some looms, especially those of more than usual width, it may be desirable to further brace the feelers and also the drop wire guides, and to this end the feeler carrier is provided with braces 75 having notched portions 76, Fig. 2, which engage the top edge portions of the feelers. In the present instance the feeler braces 75 may be mounted upon the connecting member 65 of the feeler carrier by collars or sleeves 77, and secured thereto by the set screws 78.

Extending between the brackets 41 is the brace supporting rod 79, Fig. 2, which may be appropriately secured to the brackets by set screws 80. Mounted upon and fixed to the rod 79 are the arms 81 of which there may be any suitable number, having secured thereto the drop wire guide braces 82 which are notched, as indicated in Fig. 2, for the reception of the drop wire guides 45.

The feelers have a drop wire engaging portion which is given its detecting movement in the horizontal plane of the drop wire guides in order that the drop wire guides may support the drop wires directly in the plane of detecting movement of the feelers when the latter are arrested by a fallen drop wire. By thus backing up the drop wires under the detecting action of the feelers, a single drop wire guide is sufficient,

in most cases, for a row of drop wires, without distorting the drop wires. Inasmuch as the feelers are mounted in an inclined position, as indicated in Figs. 4 and 5, the lower 5 portions of the feelers are cut-away or beveled, to provide an engaging portion in the horizontal plane of the drop wire guides.

When it is desired to run the loom without stopping, due to a warp fault, the loom 10 attendant lifts the feeler carrier from its operating relation with the drop wires, as indicated in Figs. 2 and 3; and in the present instance, detaches the feeler carrier from its operating means. This he is enabled to do 15 more readily because the feelers are supported by the feeler carrier above the plane of the warp threads. When the loom has run sufficiently long to condition the warp threads properly, the attendant has only to 20 return the feelers back to their operative condition with respect to the drop wires.

When the drop wires are supported in their raised position by the warp threads, they should be sufficiently free of the drop 25 wire guide to permit sensitive response of the drop wires to a slack or broken warp thread, and yet when the drop wire has responded to the warp fault, it should be in sufficiently close engagement with the guide 30 to prevent give or lost motion as the feeler presses against the enlarged portion of the drop wire. To this end each drop wire has the elongated slot 46 which is engaged by the flat guide, and sufficient clearance is 35 provided between the guide and the walls of the slot 46 to permit the drop wire to drop when it fails to be supported by a warp thread. At its upper end and backing the enlarged part 48 of the drop wire, the 40 slot 46 is narrowed to substantially fit the guide 45 without material clearance. To this end the wall of the slot adjacent the enlargement 48 is carried closer to the opposite wall of the slot, thereby not only narrowing 45 the slot, but by moving the drop wire laterally toward the feeler, as the drop wire moves into stopping relation with the feeler, the part 48 can be made less large than otherwise would be necessary, thereby 50 lessening the space fore and aft of the loom occupied by the warp stop motion proper.

The construction described as a good practical form of the present invention is simple and efficient in operation, and by combining 55 the parts in the relation described with the feelers above the plane of the warp threads, not only does the warp stop motion not materially interfere with the size of warp beam or wound warp on the beam, but the 60 feelers are rendered accessible and readily removable from operative position by the loom attendant when it is desired to run the loom without stopping due to a warp fault. The reciprocating movement given to the 65 feelers in a path above the warp threads and

by means at each side of the loom enables the feelers to be made of sufficient rigidity to withstand the arresting action of a drop wire without flexing or bending the feeler, a condition which is further insured by the 70 inclined position of the feelers. An important feature contributing to the advantages flowing from the present invention, is the fact that the feelers are not only supported in position above the plane of the 75 warp threads but are mounted on side members of a feeler carrier which is supported and operated for ready removal as a whole from operative position. The side members of the feeler carrier in the preferred form 80 of the invention include between them the entire series of drop wires and drop wire guides, so that no obstruction is offered to the removal of the feeler carrier.

What is claimed is:

1. In a warp stop mechanism for looms, the combination of a series of drop wires normally supported by the warp threads during weaving, a feeler carrying frame comprising side members, a feeler carried by the 90 feeler carrying frame above the warp threads, a transverse bar extending between and secured to the side members of the feeler carrying frame, an actuator for imparting detecting movements to the feeler carrying frame, and connections between the transverse bar and actuator unobstructing removal of the feeler carrying frame from operative position.

2. In a warp stop motion for looms, the combination of a series of drop wires adapted to be supported by the warp threads during weaving, a feeler carrying frame comprising side members having arms projecting therefrom, feelers extending between the 100 side members of the feeler frame and supported above the plane of the warp threads, a transverse reinforcing bar which extends between and is secured to the arms of the side members and has its end portions extending beyond the said arms, an actuator, and connections between the actuator and the projecting portions of the transverse reinforcing bar unobstructing removal of the feeler carrying frame and feelers from operative relation with the drop wires.

3. In a warp stop motion for looms, the combination of a series of drop wires adapted to be supported by the warp threads during weaving, a feeler carrying frame comprising side members and feelers extending between the side members, a transverse reinforcing bar extending between and connecting the side members of the feeler frame, a rock shaft having operating arms, and connections between the operating arms and the transverse reinforcing bar unobstructing removal of the feeler carrying frame and feelers from operative relation with the drop wires.

4. In a warp stop motion for looms, the combination of a series of drop wires adapted to be supported by the warp threads during weaving, a feeler carrying frame comprising side members and feelers extending between the side members, a transverse reinforcing bar extending between and connecting the side members of the feeler frame, a rock shaft having operating arms, a supporting saddle adjustably mounted on each of the operating arms for engaging the transverse reinforcing bar when the feeler carrying frame is in operative position, and connections between the operating arms and transverse reinforcing bar unobstructing removal of the feeler carrying frame and feelers at will from operative position.
5. In a warp stop motion for looms, the combination of a series of drop wires adapted to be supported by the warp threads during weaving, a feeler carrying frame comprising side members, feelers extending between the side members above the plane of the warp threads a transverse reinforcing bar on which the side members of the feeler carrying frame are secured, feeler braces mounted on the reinforcing bar and engag-

ing the feelers between the side members, an actuator for the feeler carrying frame, and connections between the actuator and the transverse reinforcing bar which unobstruct removal of the feeler carrying frame, feelers, transverse reinforcing bar, and braces as a unit from operative position relative to the drop wires.

6. In a warp stop motion for looms, the combination of a series of drop wires adapted to be supported by the warp threads during weaving, a feeler carrying frame comprising side members, feelers extending between the side members above the plane of the warp threads, a transverse reinforcing bar on which the side members of the feeler carrying frame are secured, a rock shaft, arms secured to the rock shaft and each having an open slotted end for engaging the transverse reinforcing bar and unobstructing removal of the feeler frame, feelers, and transverse reinforcing rod as a unit from operative position.

In testimony whereof, I have signed my name to this specification.

EDWARD S. STIMPSON.
